UNITED STATES PATENT OFFICE.

JOHN HENRY, OF GRAND FORKS, NORTH DAKOTA.

GRAIN-DOOR.

1,029,061.

Specification of Letters Patent. Patented June 11, 1912.

Application filed February 14, 1911. Serial No. 608,510.

To all whom it may concern:

Be it known that I, JOHN HENRY, citizen of the United States, residing at Grand Forks, in the county of Grand Forks and State of North Dakota, have invented new and useful Improvements in Grain-Doors, of which the following is a specification.

My present invention has to do with grain doors for cars; and it has for its object to 10 provide a simple door calculated to withstand the rough usage to which analogous doors are ordinarily subjected, and constructed with a view to being quickly and easily opened when it is desired to discharge 15 grain or other substance carried in bulk from the car.

The invention will be best understood by reference to the following description when taken in connection with the accompanying 20 illustration of specific embodiments thereof, while its scope will be more particularly pointed out in the appended claims.

In the drawings which are hereby made a part hereof: Figure 1 is an elevation, partly 25 in section, illustrating my novel door as it appears from the outside of the car. Fig. 2 is an enlarged vertical section taken in the plane indicated by the line 2—2 of Fig. 1, looking toward the left. Fig. 3 is an enlarged horizontal section taken on the line 30 3—3 of Fig. 1, looking downward. Fig. 4 is a view taken at a point within the car and illustrating one section of the door as lifted out of operative position and fastened 35 out of the way against the side wall of the car. Fig. 5 is a horizontal section taken in the plane indicated by the line 5—5 of Fig. 4, looking downward. Fig. 6 is a detail section taken on line 6—6 of Fig. 4 and showing 40 the fastener for securing the door section in idle position. Fig. 7 is a view taken at a point within the car and illustrating as closed a modification of my invention hereinafter referred to in detail. Fig. 8 is 45 a horizontal section taken in the plane indicated by the line 8—8 of Fig. 7, looking downward.

Referring by letter to the said drawings, and more particularly to Figs. 1 to 6 50 thereof: A is the door opening in the car wall. Above the said opening A a recess or space B is provided with which communicate small recesses C in the door posts D, as will be understood by comparison of 55 Figs. 2 and 4. The communicating space B and recesses C are designed to receive the

door-sustaining bar E when the said bar is swung up into its idle position; the said bar being provided with arms a, pivoted at b to the posts D, and being designed to be fastened in the space B and recesses C by any suitable means in the event that any means whatever is deemed necessary for the purpose. The bar E is of I-form in cross-section, Figs. 1 and 2, and is designed when in its lower, working position to rest in recesses e in the posts D, as clearly shown by full lines in Fig. 2, the upper and idle position of the bar being indicated in the same figure by dotted lines. 70

Rabbets F are suitably provided at the inner sides of the door posts D, and connected to the inner sides of the posts are keepers G which terminate in outwardly extending portions d, Figs. 3 and 4, which portions d are spaced from the outer walls of the said rabbets F. It will also be observed by reference to the drawings that a strip H, preferably of metal, is arranged at the lower end of the door opening A, and that small strips I, Figs. 2, 3 and 4, are arranged on the car floor at a slight distance inward from the said strip H. It will further be observed by reference to Figs. 1 and 2, that a keeper J is arranged on the inner 75 side of one of the door posts D for a purpose hereinafter set forth. 80

In addition to the parts thus far described, my novel door comprises a movable door section K and a movable door section 90 L; the said sections being preferably, though not necessarily, connected with the car wall through the medium of chains M. By reference to Figs. 1 and 2, it will be seen that the section K is provided with a hook 95 e to engage the bar E and hold the section thereagainst, and that said section K is also provided on its outer side with a projection f, and with a swinging latch g, and a locking bar h therefor; the projection f being 100 arranged near the lower end of the section so as to permit of the ready interposition of a crowbar between it and the plate or strip H, and the latch g and locking bar h being so arranged relative to the keeper J that 105 the latch can be swung into engagement with the underside of the keeper J so as to hold the door down, and being designed to be retained in said engagement by the locking bar h in the position shown in Fig. 1. 110 When the locking bar h is swung on its pivot i away from the latch g, the said

latch is free to swing out of engagement with the keeper J, and then the door section K can be raised rectilinearly by a prying instrument positioned between projection *j* and strip H.

For the purpose of holding the door section L down, I provide the said section on its outer side with a thin projection *j* which is adapted when the section is placed in its closed position, to assume a position directly under the bar E. From this it follows that when the bar E and door section L are relatively arranged, as shown in Fig. 1, the bar E will operate to prevent rectilinear upward movement of the section L.

While I prefer to employ some suitable means, the devices described, for instance, for holding the door sections K and L down in their working positions, I do not desire to be understood as confining myself to the employment of means for the purpose, inasmuch as when deemed expedient the weight of the sections K and L may be depended on to hold the same against casual upward movement.

The opposed edges of the sections K and L are inclined slightly from the vertical, Figs. 1 and 3, so that the section K is slightly wider at its upper end than at its lower end, while the lower end of the section L is wider than the upper end thereof. It will also be observed that the section L is provided at its outer side with a flange *k* that extends beyond its inner edge, and is designed to break joints with the inner edge of the section K, so as to prevent the escape of grain or other substance between the opposed edges of the sections when the same are closed. At their outer edges and inner sides the sections K and L are rabbeted throughout their height so as to afford narrow outer edge portions *l* designed to rest in the rabbets F of the door posts and between the outer walls of said rabbets and the outwardly directed terminals *d* of the keepers G on the posts.

For the purpose of fastening the sections K and L against the inner side of the car wall and out of the way when said sections are not in use, I prefer to employ the means illustrated in Figs. 4 to 6, with reference to the door section K, it being understood that similar means will be employed in connection with the door section L. It will be observed that one end of the section K is arranged at the inner side of an angle plate P, and that the other end of the door is engaged by a spring fastener R, so that when the door rests on the ledge S provided for its support, the door or door section will be securely held against casual displacement. The fastener R is, because of its resiliency, movable at right angles to the car wall and also in a plane or planes parallel to said car wall, and from this it follows that the plate

t on the fastener may be readily engaged with the adjacent end of the section K, to secure said section, and may as readily be disengaged from the end of the section to release the same.

The practical operation of my improvements is as follows: When the sections K and L are closed, as shown in Figs. 1, 2 and 3, and it is desired to open the door, the latch *g* is disengaged from the keeper J, and then the section K is raised rectilinearly by a crowbar or other means until the grain adjacent the door has run out. Then the section K is pushed into the car, after which the operator takes hold of the upper end of section L and cant or pulls said end toward the remote side of the doorway, when the grain adjacent said section L will pass out between the outer edge of the section L and the adjacent post, and will also run out below the raised portion of the lower edge of the section L.

To close the door, the section L is positioned as shown in Figs. 1 and 3, with its reduced edge *l* in the rabbet F and between the keeper G and the outer wall of the rabbet, and so that the lower end of said section rests between the strip H and one of the strips I. The other section K is then, while in an elevated position, placed with its reduced edge *l* between the other keeper G and the outer wall of the rabbet F in the other post, and is then moved down rectilinearly, with its inner edge resting at the inner side of the flange *k* on the section L until its lower end rests between the strip H and the other strip I.

With the door sections K and L closed as stated, it will be manifest that an effectual closure of the lower portion of the door opening A is accomplished, and that there is no liability whatever of the door bulging outward under the pressure of grain within the car, and no liability of either of the sections K, L being casually displaced. After the sections K and L are removed to permit the passage of grain through the door opening, the bar E can be readily adjusted so as to leave the door opening entirely clear.

While convenient for the purpose of holding the door sections K and L against the bar E and the outer walls of the rabbets F, the hook *e* and the keepers G or other devices for the same purpose, are not essential to the successful practice of my invention, and therefore such devices may be omitted without involving departure from the scope of my invention as claimed.

The modified construction shown in Figs. 7 and 8 comprises door sections K⁷, L⁷ and M⁷; the said sections being arranged relative to the strips on the floor, the bar E, the posts D and the keepers J, as well as the strips H and I on the car floor, in the same manner as the before described sections K

and L. The inner edges of the sections K' and L' are inclined slightly from the vertical and so that said edges converge downwardly. It will also be seen in Fig. 8 that the sections K' L' are provided at their outer sides with flanges W' which extend inward beyond their inner edges and are continuous throughout their length. These flanges, when the parts are positioned as shown in Figs. 7 and 8, serve to break joints with the intermediate section M', and in that way preclude the escape of grain or other substance carried in bulk between the opposed edges of the sections.

15 While I have shown and described certain forms of my invention, it is to be understood that I am not limited to the details or the form or relative arrangement of parts disclosed, but that modifications may be 20 made therein without departing from the spirit thereof.

Having described my invention, what I claim and desire to secure by Letters-Patent, is:

25 1. In a grain door for cars, the combination of a car body having a door opening and door posts, a door-sustaining bar carried by the car body, and a door bearing outward against the bar and posts and comprising sections the opposed edges of which are inclined from the vertical, whereby one section is wider at its upper end than at its lower end and the adjoining section is wider at its lower end than at its upper end, and 35 also comprising a flange on one section and extending beyond the edge thereof and overlapping the opposed edge of the other section.

2. In a grain door for cars, the combination of a car body having a door opening and door posts, a door-sustaining bar carried by the car body and extending crosswise of the opening, a keeper arranged on one of the posts, and a door bearing outward 40 against the bar and posts and comprising sections the opposed edges of which are inclined from the vertical and also comprising a flange on one section and extending beyond the edge thereof and overlapping the 45 edge of the other section; the section adjacent the post that bears the keeper being wider at its upper end than at its lower end and being provided with detachable means for engaging the keeper and holding the section against upward movement.

3. In a grain door for cars, the combination of a car body having a door opening and door posts, a door-sustaining bar carried by the car body and extending crosswise of the opening, a keeper on one of the door posts, and a door bearing outward 50 against the car body and bar and comprising sections the opposed edges of which are inclined from the vertical and also comprising 55 a flange on one section and extending be-

yond the edge thereof and overlapping the edge of the other section; the section that is widest at its upper end being arranged adjacent the keeper-bearing post, and being provided with means for detachably engaging said keeper and with other means for engagement with the bar to hold the section thereagainst, and the other section being provided with means for bearing upward against the underside of the bar.

4. In a grain door for cars, the combination of a car body having a door opening and door posts, means for preventing outward movement of a door, keepers on the inner portions of the posts, and a door bearing outward against the said means and the posts and interposed between said keepers and the posts and comprising sections the opposed edges of which are inclined from the vertical and between which edges the joint is broken.

5. In a grain door for cars, the combination of a car body having a door opening and door posts, a door-sustaining bar carried by the car body and extending crosswise of the opening, keepers on the inner portions of the door posts, a keeper on the side of one post toward the door opening, and a door interposed between the first-named keepers and the posts and bearing outward 90 against the car body and crosswise bar and comprising sections the opposed edges of which are inclined from the vertical and between which edges the joint is broken; the section that is widest at its upper end being 95 arranged adjacent the post on the side of which toward the door opening is the keeper and being provided with means for detachably engaging said keeper and with other means for engagement with the bar to hold the section thereagainst, and the other section being provided with means for bearing upward against the bar.

6. In a grain door for cars, the combination of a car body having a door opening and means in the door opening for preventing outward movement of a door, and a door bearing outward against the car body and the said means in the door opening and comprising separable and movable sections 110 the edges of which are inclined from the vertical and opposed and between which edges the joint is broken.

7. The combination of a car body having a door opening and a horizontal ledge inside the body at one side of said opening, a door movable from the opening to said ledge and vice versa, a keeper in the body adapted to hold one end of the door against lateral movement off the ledge, and a resilient fastener on the inside of the body and movable by virtue of its resiliency longitudinally and transversely of the same to engage and disengage the other end of the door on the ledge.

8. In a grain door for cars, the combination of a car body having a door opening and door posts, a door-sustaining bar extending crosswise of the door opening, and a door bearing outward against the bar and posts and comprising sections the opposed edges of which are inclined from the vertical, whereby one section is wider at its upper end than at its lower end and the adjoining section is wider at its lower end than at its upper end, and also comprising a flange on one section and extending beyond the edge thereof and overlapping the opposed edge of the other section.
9. In a grain door for cars, the combination of a car body having a door opening and door posts, a door-sustaining bar extending crosswise of the door opening, and a door bearing outward against the said bar and the posts and comprising sections having opposed edges and also having the joint between said edges broken.
10. In a grain door for cars, the combination of a car body having a door opening and door posts, a door-sustaining bar extending crosswise of the door opening, keepers on the inner portions of the posts, and a door bearing outward against the said bar and the posts and interposed between said keepers and the posts and comprising sections the opposed edges of which are inclined from the vertical and between which edges the joint is broken.
11. In a grain door for cars, the combination of a car body having a door opening and door posts, means on the posts for preventing lateral movement of a door, a door

comprising vertical sections disposed between said means on the posts and bearing outward against the posts, means for preventing outward movement of the lower portions of the door, and a crosswise bar for the upper portions of the door to bear outward against.

12. In a grain door for cars, the combination of a car body having a door opening and door posts, means on the posts for preventing lateral movement of a door, a door comprising vertical sections one of which is adapted to be raised for the discharge of grain, means for preventing outward movement of the lower portions of the door, and a crosswise bar for the upper portions of the door to bear outward against.

13. In a grain door for cars, the combination of a car body having a door opening and door posts, means on the posts for preventing lateral movement of a door, a door comprising vertical sections having opposed edges; one of the said sections being wider at its upper end than at its lower end and being adapted to be raised for the discharge of grain, means for preventing outward movement of the lower portions of the door, and a crosswise bar for the upper portions of the door to bear outward against.

In testimony whereof I have hereunto set my hand in presence of two subscribing witnesses.

JOHN HENRY.
